[57] CLAIM

The ornamental design for a child's swing, as shown and described.

DESCRIPTION

FIG. 1 is a front elevational view of a child's swing showing our new design;

FIG. 2 is a top view of the swing of the present invention;

FIG. 3 is a right side elevational view of the swing of the present invention, with the left elevation view being a mirror image thereof;

FIG. 4 is a rear elevational view of the swing of the present invention; and,

FIG. 5 is a bottom view of the swing of the present invention.

FIG. 1

FIG. 2

FIG. 3

FIG. 4

FIG. 5
